UNITED STATES PATENT OFFICE.

WILLIAM FREDERICK McMAHON, OF RIVERSIDE, CALIFORNIA.

DIVISION-HEAD PROPELLING SCREEN.

Application filed March 14, 1927. Serial No. 175,280.

This invention relates to a novel construction for propelling a material through a perforated screen that is adapted to keep a certain grinding media in its respective place in a crushing or grinding mill, and has for its object improvements in devices for this purpose of the kind in which the rotary action of the mill shell is utilized as the motor medium in cooperation with the spiral or helical formation of the perforated screen to effect positive delivery of the material through the perforations in the screen.

Another object is to provide a perforated screen that will have a spiral screw action on the material that comes in contact with it, whereby the material is propelled through it.

A further object is to provide a perforated screen that will automatically prevent the perforations in it from clogging.

Heretofore it was thought that the relative low efficiency of a grinding mill was mainly due to the grinding media therein, I discovered by research that the grinding media in all grinding mills is highly efficient, and that the low efficiency was directly due to the perforated screen in same, retarding the flow of the ground material from discharging out of the mill or from entering the adjacent compartment.

In other words, the function of a screen in a grinding mill is mainly to keep the grinding media in place in its respective compartment and at the same time allow all material that reaches it to pass through it to the next compartment in the grinding mill.

Also the size mesh of the material discharged from a mill or compartment depends directly upon the length of the mill or compartment relative to the grinding media and the size of the material feed.

It should be noted that all material in a grinding mill travels substantially in a set channel in the grinding media and when said material has passed through the length of the compartment, upon reaching the screen should be immediately passed through the screen to prevent the retarding of the incoming material, therefore in all present screens depending upon weight of the mass of the material to force the same through a fast revolving perforation, it suffices to say that if the material was positively delivered through the perforations the latter would be most efficient means.

Also the entire body of ground material adjacent the said screen lays in a sector of the grinding media in one segment of the mill near its shell, hence by my radial perforations it will be seen that each perforation will come in contact with the entire body of ground material making thereby a highly efficient discharge.

Technically speaking what governs the horsepower of the grinding mill is the weight of the mill plus the weight of the grinding media and material in same and plus the weight of the screen, relative to the speed of the said mill. The screen in the mill plays but a small part in the horsepower formula outside of its weight, regardless of what type of screen it is, but you can readily see that if all material that reaches it, is immediately passed through the said screen, you will get a higher production from the grinding mill with substantially the same horsepower than you would if the ground material was retarded from passing out of the mill and was continually distributed over the grinding media in the mill.

With these and other objects in view, the invention resides and consists in the construction and novel combination and arrangement of parts hereinafter more fully described, and illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1 is an end view of my division head propeller screen, taken on the grinding media side of the screen, showing two segments of the screen in position, with three segments omitted, these omitted segments will be similar to the two segments shown, also showing the general formation of the screen supporting arms.

Fig. 2, is a sectional elevation at "a—a" of Figure 1, and Figure 3.

Fig. 3, is an end view of the division head propeller screen taken on the discharge end

of the same and showing in particular the general construction of the solid wall segments, and the discharge opening.

Fig. 4, is a sectional view at "c—c" of Figure 1, showing the general spiral or helical formation of the screen segments and the inclined perforations in same, also showing the typical section through the arm at "b—b" in Figure 5.

10 Fig. 5, is a detailed plan view of the arm.

Fig. 6, is a side view of Figure 5, this view is on a third angle projection relative to Figure 5.

15 Fig. 7, is the other side view of Figure 5, this view is also on a third angle projection, relative to Figure 5.

Fig. 8, is a detailed plan view of a perforated screen segment, showing the radial perforations.

20 Fig. 9, is a section at "d—d" of Figure 8, showing the rearwardly inclined perforations.

Fig. 10, is a detailed plan view of the combined spout and lifter.

25 Fig. 11, is a section at "e—e" of Figure 10

Referring in detail to the characters of reference marked upon the drawings, 1 represents the shell of grinding mill that encases the shell liners 2 which are provided 30 as a wearing plate for the grinding media in the mill. As the construction and operating principle of a grinding mill is well known I will only describe the parts pertaining to my invention as all other description would be superfluous. While this division head screen is substantially the same construction as the propeller screen shown in my copending application Serial Number 146,262, and filed on or about the 4th

35 40 day of November 1926, this present application contains a more specific specification and illustrations and pertains to the specific construction of a division head propeller screen as applied to compartment or compeb mills, which is the commercial name of this particular type of grinding mill.

45 This compartment grinding mill may contain several respective compartments for the purpose of each compartment containing a specific grinding media. In my application Serial Number 146,262, I have shown a typical screen for ball mills and tube mills. A compartment or compeb mill is a combined ball and tube mill, the division head screen 50 illustrated in the appended drawings here-with is the division head between the said ball and tube mill compartments.

55 I desire to plainly note at this time that my propeller screen is not provided for the purpose of actuating the grinding media to increase the grinding action of same upon the material being ground, but the said propeller screen is provided to propel all material that comes in contact with it through 60 the perforations in it employing the same

principle as a propeller blade on water, or a similar action as a spiral screw conveyor.

To accomplish this said propeller blade action upon the material, I provide a construction similar to a spoked wheel having 70 an inner hub 3, arms or spokes 4, and an outer rim 5.

This said wheel construction forms a circular ring sector space 6 between each arm 4 and in this circular ring sector space 1 75 place my perforated screen 7 on an inclination, as clearly shown in Figure 4. The entire screen 7 being inclined toward the direction of rotation of the shell 1 as indicated in the several figures of the illustrations 80 by the arrows.

While the screen 7 is inclined in horizontal section toward the direction of rotation of the shell 1, it is also inclined in an outer direction from the hub 3 toward the 85 rim 5. To effect these said inclinations I provide a supporting lug 8, which will be practically level on one side of the arm 4 and an inclined supporting lug 9 on the opposite side of the arm 4. The arm 4 90 proper being substantially vertical to allow a general vertical support for the entire division head.

By referring to Figures 5, 6 and 7 will be seen the general construction of each arm, 95 which will contain an inner hub 10, that contains a groove 11 for the lifter 12. Also there are outer disposed rim supports 13 which will be inclined to suit the inclinations of the screen 7. Holes 14 are provided for bolts 15 100 that fasten the back plates 16 and 17 together with the lifters 12 to the arm.

The general construction of the lifter 12 will be seen by referring to Figures 10 and 11, and lifter 12 is provided to act as a spacer 105 between the arm 4 and the back plates 16 and 17. It has a hub 18 formed into a spout 19 and an outward disposed portion 20 that will contain the two holes 21 for the bolts 15. This lifter 12 actuates the material that 110 has passed through the screen 7 to the discharge opening 22, and forms a discharge space 23 between the back plates 16 and 17 and the screens 7.

The back plates 16 and 17 are formed the 115 shape of circular ring sectors, the outer plate 16 having a groove 24 to mesh with the inner plate 17. In this particular construction I have shown these back plates separated at the center of the lifter 12. It is 120 at this joint 25 I place my holding bolts 15. To prevent wear on the bolt heads 26 these heads 26 are set into the plates. The inner plate 17 containing the discharge opening 22 is held in place by it bearing onto the lifters 12 and by means of the bolts 15, also by the fact that the plates bear against each at the said joint 25. It is to be noted that the outer plate 16 bears onto plate 17 and is held 125 in place by the shell liners 2. 130

It may be well to state at this time that the entire division head is held in place in the grinding mill by the shell liners 2, an adjusting liner 27 cooperates with the said shell liners 2 and provides a take up means at the assembly.

Bolt 28 fastens the several arm segments with the several lifters 12. While I have shown but one bolt performing this said function, several bolts may be provided to do this work if it is so desired.

The outer rim 5 forms the connecting link between the arms 4 and contains an inclined groove 30 so arranged as to support the screen 7, it also contains an outward disposed portion 29 that serves as a spacer between the screen 7 and the plate 16. This portion 29 tends to hold the screen 7 in place in relation to the arms 4 and plates 16 and shell liners 2.

The screen 7 is substantially a circular ring sector comprising a series of radial perforations 31 inclined rearwardly relative to the movement of the screen. It should be noted that these said perforations do not have to be inclined toward the direction of the movement of the screen rearwardly to get a spiral action on the material. But any form of perforation put into this screen will have a substantially propeller action on the material as this entire screen is inclined toward the direction of the movement of the said grinding mill. However a rearwardly inclined perforation is preferable because it tends to prevent the perforations from clogging. The screen 7 is held stationary in place in the division head by supporting lugs 8 and 9 in the arms 4, and by the rim 5 on one side. On the opposite side the shell liner 27 holds it in place together with a plate 32 that has a bolted connection with the arm 4.

It should be noted that in this novel construction each screen 7 or circular ring sector is separated by an arm 4 making thereby an independent propeller blade of each sector. The general construction of the assembled sectors or screens being of a so called sawtooth formation each screen being independent of the other and sloped toward the direction of the movement of the mill. So that regardless of what the shape of the perforation is therein, the tendency of each individual screen will be to function as a propeller blade and positively effect the delivery of all material that comes in contact with it through the perforations in it. However a radial perforation is in my mind preferable because each perforation will be swept through the entire body of material in the mill.

Having thus described my invention, what I claim and desire to secure by Letters Patent is,

1. In a grinding mill, the combination with a rotary shell, of a division head com-

prising a series of separating screens inclined transversally between two radii.

2. In a grinding mill, the combination with a rotary shell, of a division head comprising a series of separating screens inclined transversally between two radii and being so formed as to cause a positive passage of the material therethrough. 70

3. In a grinding mill, the combination with a rotary shell, of a division head comprising a series of separating screens inclined transversally between two radii and being so formed as to cause a positive passage of the material therethrough, spaced means separating the screens. 75

4. In a grinding mill, the combination with a rotary shell, of a division head comprising a series of separating screens inclined transversally between two radii and being so formed as to insure a positive delivery movement of the ground material. 80

5. In a grinding mill, the combination with a rotary shell, of a division head comprising a series of separating screens being so formed as to insure a positive delivery movement of the ground material therethrough, spaced means between the said screens, and means for securing the separating screens to the first named means. 90

6. In a grinding mill, the combination with a rotary shell of a division head comprising a series of separating screens inclined transversally between two radii and being so formed as to insure a positive delivery movement of the ground material therethrough, spaced means separating the said screens, and means for securing the said separating screens stationary with the said rotary shell. 95

7. In a grinding mill, the combination with a rotary shell, of a division head comprising a series of separating screens inclined transversally between two radii and being so formed as to cause a positive passage of the material therethrough, spaced arms separating the screens, an inner hub, an outer ring, said arms forming connecting means between the hub and ring, a partition wall comprising a discharge opening, spaced separators forming a spout between the wall and arms, and means for securing the said separating screens stationary relative to the said rotary shell. 105

8. In a grinding mill, the combination with a rotary shell, of a division head comprising a series of separating screens inclined transversally between two radii and being so formed as to cause a positive delivery movement of the material therethrough, a partition wall comprising a discharge opening, a delivery space between the separating screens and partition wall, and means for securing the separating screens and partition wall stationary relative to the said rotary shell. 120

9. In a grinding mill, the combination with a rotary shell, of a division head comprising a series of separating screens inclined transversely between two radii and being so formed so as to cause a positive delivery movement of the material therethrough, spaced means separating the separating screens, a partition wall comprising a discharge spout, a delivery space between the separating screens and partition wall, and means for securing the division head stationary relative to the rotary shell.

Signed at Riverside, in the county of Riverside and State of California this 8th day of March 1927.

WILLIAM FREDERICK McMAHON.
